(57) **CLAIM**

The ornamental design for a collapsible saw horse, as shown and described.

DESCRIPTION

FIG. 1 is a perspective view of a collapsible saw horse, showing our new design;

FIG. 2 is a left side elevation view thereof;

FIG. 3 is an enlarged partial view of a portion thereof, taken from FIG. 2;

FIG. 4 is a top plan view thereof;

FIG. 5 is a bottom plan view thereof;

FIG. 6 is an enlarged view of a portion thereof, taken from FIG. 4;

FIG. 7 is a right side elevation view thereof;

FIG. 8 is a rear elevation view thereof; and,

FIG. 9 is a front elevation view thereof.

The broken lines shown in the drawings depict portions of the collapsible saw horse that form no part of the claimed design.
